UNITED STATES PATENT OFFICE.

FREDERICK W. BAUMANN, OF MONTCOTT BOROUGH, PENNSYLVANIA, AS-SIGNOR TO OLIVER IRON AND STEEL COMPANY, OF PITTSBURG, PENNSYLVANIA, A CORPORATION OF PENNSYLVANIA.

METHOD OF FORMING BRAKE-BEAM FULCRUMS.

No. 843,659.

Specification of Letters Patent.

Patented Feb. 12, 1907.

Application filed March 27, 1906. Serial No. 308,295.

To all whom it may concern:

Be it known that I, FREDERICK W. BAUMANN, a resident of Montcott borough, in the county of Allegheny and State of Pennsylvania, have invented a new and useful Improvement in Methods of Forming Brake-Beam Fulcrums; and I do hereby declare the following to be a full, clear, and exact description thereof.

My invention relates to a method of manufacturing parts of brake-beam fulcrums.

In that type of brake-beam fulcrums in which the fulcrum is formed of two parts shaped so that when united they form a recess to receive the flange of an I-beam forming the brake-beam, as well as an angular recess to receive the brake-lever, it has been a matter of great difficulty to obtain the proper shape of the parts without a number of operations which distorted and weakened the metal at certain points where said parts are made of wrought-metal.

The object of my invention is to provide a method by means of which the operations required for shaping the parts forming the fulcrum are reduced, thereby reducing the strain on the metal and at the same time the time and labor.

In the accompanying drawings, Figure 1 represents a plan view of a suitable machine for carrying out the first step of my improved method. Fig. 2 is an enlarged plan view of the dies. Fig. 3 is an end view of same. Fig. 4 is an opposite end view. Fig. 5 is a cross-section on the line 5 5, Fig. 2, showing the dies closed. Fig. 6 is a cross-section on the line 6 6, Fig. 2, showing the dies closed. Fig. 7 is a cross-section on the line 7 7, Fig. 2, showing the dies closed. Fig. 8 is a vertical elevation of the apparatus for forming the second step of my improved method. Fig. 9 shows a plan view of the dies side by side. Fig. 10 is an end view of the dies. Fig. 11 is a section on the line 11 11, Fig. 9. Fig. 12 is a section on the line 12 12, Fig. 9. Fig. 13 is a vertical section through the dies on the line 13 13, Fig. 12. Figs. 14 and 15 show the views of the blank after the first operation. Figs. 16 and 17 show it in the finished form, and Fig. 18 is a view of the finished fulcrum in the construction of which the above parts are used.

Like numerals indicate like parts in each of the figures.

In the drawings the numeral 2 designates the framework of a suitable swaging-machine, in which is journaled the shaft 3, driven by power applied to the pulley 4. The shaft is provided with the fly-wheel 5. At one end of the shaft 3 is the pinion 6, which meshes with the gear 7. Arranged eccentrically of the gear 7 are wrist-pins 7^a, to which the pitmen 8 are connected and to the cross-head 9, to which the die 10 is secured. Secured to the bed-plate of the machine opposite the moving die 10 is the stationary die 11. The die 10 has secured to one end thereof the stop or gage 12. The working face of the die 10 has the recess 10^a, formed therein with the overhanging portion 10^b. Below the overhanging portion 10^b is the projecting portion 10^c, with the inclined face 10^d, forming part of the recess 10^a. The projecting portion 10^c is provided with the beveled lower face 10^e. Adjacent to the overhanging portion 10^b and projecting portion 10^c is the projecting rounded or curved rib 10^f with the depressions 10^g on each side thereof. Beyond the curved rib 10^f is the overhanging portion 10^g. The opposite die 11 works in conjunction with the die 10, and opposite the overhanging portion 10^b of the die 10 is the corresponding overhanging portion 11^a and a portion 11^b, which has a beveled face 11^c corresponding to the beveled face 10^e, so that when the dies are closed they will together compel the metal to assume the position indicated in Fig. 6.

Opposite the curved portion 10^f of the die 10 the die 11 has the projecting portion 11^d, which when these dies are closed, as indicated in Fig. 5, compels the metal to assume the position indicated in said figure, the metal being crowded at this point into the depression 10^g, so as to conform to the curved face 95 of the portion 10^f of the die 10. The die 11 has the portion 11^e, which acts in conjunction with the beveled face 10^h of the die 10, so that when the dies are closed, as indicated in Fig. 7, the metal at that portion of the dies will assume the position there indicated.

In Fig. 8 the numeral 14 indicates a suitable drop-board hammer carrying the die 18, moving in suitable guides 19. Below is

secured the stationary die 20. In Fig. 9 I have illustrated these dies side by side, the lower die 20 having the flat recess 21 and the cross groove or depression 22 and beyond said groove the recess 17, with inclined face 23. The upper die 13 has a flat portion 24, corresponding to the flat portions at the sides of the recess 21 of the lower die and projecting cross-rib 25, which is adapted to enter the groove 22 of the die 20. The die 18 has the projection 26, with the inclined face 26^a corresponding to the inclined face 23 of the die 20. It also has a slight V-shaped recess 27 to receive one edge of the bar, as indicated in Fig. 12. When the dies are brought close together, as indicated in Fig. 12, the metal will be compelled to assume the position indicated therein.

In carrying out my improved method with the above-described apparatus I first take a bar of wrought metal of suitable dimensions and having heated same introduce it between the dies of the machine indicated in Fig. 1, the forward end of the bar abutting against the stop 12. Power is then applied to move the die 10 toward the die 11, whereupon the opposite faces of the dies act as indicated in the several cross-sectional views 5, 6, and 7 to impart the shape to the metal, as indicated in said figures. For instance, the overhanging portion 10^b and 11^a, together with the portions 10^c and 11^b, act to throw that portion 31 of the straight bar in contact with said faces into the position indicated in Fig. 6, or slightly oblique to its original shape. That portion of the bar which is acted on by the curved portion 10^c and the portion 11^d will be forced to assume a curved shape, such as indicated at 28 in Figs. 14 and 15 of the drawings. The pressure being applied to the edges of the metal, the metal at this particular point will be forced up over the curved swage-block 10^c, so that when the portion 30 of said bar is twisted, as hereinafter set forth, the bend or curve 28 will be along one edge of the bar and will form a depression widest and deepest along that edge and gradually decreasing in width and depth toward the opposite edge, where at 29 there is practically no bend whatever; but the metal at this point is slightly bulged, as at 33, to form a shoulder, which is due to the twisting of the portion 30 of the bar. This portion 30 of the bar is the part that is acted on by the portions 10^e and 11^e, and these portions of the dies give the twist to this portion of the bar so as to throw it obliquely to the original line on which the bar was presented to the dies.

The bar therefore as it comes from this first operation has the shape indicated in Figs. 14 and 15, with the end portions 30 and 31 turned obliquely to each other and the intermediate curved portion 28 forming the groove or depression 32. The blank, as shown in Figs. 14 and 15, is then placed in the position in the machine 14 to be operated upon by the dies 18 and 20. As indicated in dotted lines, Fig. 9, the blank is laid on the lower die, with the portion 31 resting in the recess 21 of the die 18 and with the curved portion 28 over the groove or depression 22 and the portion 30 resting in the recess 17 against the inclined face 23. With the blank in this position the upper die is then lowered, whereupon the flat portion 24 comes down and holds the portion 31 in the flat recess 21, while the rib or tongue 25 enters the depression 32 in the blank and forces the metal down into the position indicated in Fig. 11, the face 26 conforming to the face 23, and giving the portion 30 of the blank by further twisting it the position indicated in Fig. 12. In this manner the groove 32 of the blank after the first operation, as indicated in Fig. 13, is deepened as indicated in Figs. 16 and 17, as at 34. This action of the rib or tongue 25, while it acts to deepen and narrow the groove in the blank, also acts to draw up and shorten the blank, so that the portion 31 is practically straight, while the portion 30 is oblique thereto.

By my improved method I am able to produce the parts shaped to form a brake-beam fulcrum of the type indicated in Fig. 18 with two operations, getting the peculiar twist to the blank to form the recess or groove therein without weakening the metal.

What I claim is—

The method of forming parts for brake-beam fulcrums consisting in subjecting a straight bar to pressure applied to its edges between dies, thereby twisting said bar to throw opposite portions obliquely to each other, at the same time forming between said portions a rounded depression deepest and widest along one edge of said bar and gradually decreasing in width and depth to the opposite edge, and finally subjecting said bar to further pressure increasing the depth of said depression and decreasing its width.

In testimony whereof I, the said FREDERICK W. BAUMANN, have hereunto set my hand.

FREDERICK W. BAUMANN.
